(57) **CLAIM**

The ornamental design for a bird perch, as shown and described.

DESCRIPTION

FIG. 1 is a perspective view of the bird perch.

FIG. 2 is a front view of the bird perch of FIG. 1.

FIG. 3 is a back view of the bird perch of FIG. 1.

FIG. 4 is a first side view of the bird perch of FIG. 1.

FIG. 5 is a second side view of the bird perch of FIG. 1.

FIG. 6 is a bottom view of the bird perch of FIG. 1; and, FIG. 7 is a top view of the bird perch of FIG. 1.

The broken line showing of the bird and bird food is included for the purpose of illustrating the unclaimed environment of the bird perch and forms no part of the claimed design.
